Specification for Design.

Patented Dec. 4, 1917.

Application filed October 4, 1917. Serial No. 194,826. Term of patent 7 years.

To all whom it may concern:

Be it known that I, HARRISON HEBBARD, a citizen of the United States, and a resident of East Orange, in the county of Essex and State of New Jersey, have invented a new, original, and ornamental Design for a Border for a Dish, Plate, Tray, Bowl, or Similar Article of Silver Hollow Ware, of which the following is a specification, reference being had to the accompanying drawing, forming a part thereof.

Figure 1 is a plan view of my border shown applied to a round dish.

Fig. 2 is a vertical sectional view, on an enlarged scale, on line 2—2 of Fig. 1 looking in the direction of the arrows.

I claim:

The ornamental design for a border for a dish, plate, tray, bowl, or similar article of silver hollow ware, as shown.

HARRISON HEBBARD.
